PAPER AND PENCIL HOLDING ATTACHMENT FOR TELEPHONE INSTRUMENT

Frances Louise McCracken, Washington, D.C.

Application October 22, 1958, Serial No. 53,081

Term of patent 14 years

(Cl. D26—14)

Fig. 1.

Figure 1 is a perspective view of a paper and pencil holding attachment for telephone instrument embodying my design, and showing a telephone instrument in broken lines;

The dominant features of my design are shown in full lines. The broken-line showing is for illustrative purposes only.

I claim:

The ornamental design for a paper and pencil holding attachment for telephone instrument, as shown and described.
